UNITED STATES PATENT OFFICE

ROY S. SANFORD, OF SOUTH BEND, INDIANA, ASSIGNOR TO BENDIX BRAKE COMPANY,
OF SOUTH BEND, INDIANA, A CORPORATION OF ILLINOIS

BRAKE

Application filed September 4, 1928. Serial No. 303,716.

This invention relates to brakes and is illustrated as embodied in an internal expanding brake for an automobile. An object of the invention is to provide the brake with simple and easily adjusted means for determining the idle position of a part of the friction means.

In one desirable arrangement, which is illustrated in the drawing in connection with a well known type of three-shoe brake, the articulating joint connecting two of the shoes of the brake is positioned by a novel device including a pivotally mounted lever engaging the articulating pivot and preferably interlocked therewith and which in turn is positioned by a device carried by the backing plate of the brake and which is readily adjusted from the outside of the brake and which is shown in the form of an eccentric engaging the lever.

The lever is preferably forked to engage the articulating pivot, although any suitable construction giving the necessary guide surfaces on the lever can be used, and it may be arranged either with the slot between the forked arms extending in the direction of movement of the articulating pivot, in which case the fork embraces the pivot with substantially no clearance, or at right angles to the direction of movement of the pivot, in which case the fork has sufficient clearance to allow the brake-applying movement of the articulating pivot.

The above and other objects and features of the invention, including details of the construction of the novel stop, will be apparent from the following description of the illustrative embodiments shown in the accompanying drawing, in which:

Figure 1 is a vertical section through the brake just inside the head of the brake drum and showing the brake shoes in side elevation;

Figure 2 is a partial section through the brake on the line 2--2 of Figure 1 and showing some of the details of construction; and

Figure 3 is a detailed section showing a modification, and being in effect a section on the line corresponding to the line A--A of Figure 2.

The brake in which the invention is shown embodied includes a rotatable drum 10, at the open side of which is arranged a support such as the usual backing plate 12 and within which is arranged the friction means 55 of the brake. The friction means of this particular brake includes a floating primary shoe 14 connected by a floating articulating joint or pivot 16 to a secondary shoe 18 anchored on a fixed pivot 20, together with 60 an auxiliary shoe 22 anchored on a fixed pivot 24. The brake is applied by means such as a double cam 26 which forces shoes 14 and 22 apart against resistance of a return spring 28, whereupon the shoe 14 forces 65 the shoe 18 against the drum against the resistance of an auxiliary return spring 30. In this drawing I have shown my novel stop used to determine the idle position of the articulating pivot 16, which is preferably 70 grooved adjacent the end nearest the backing plate to form an end flange 34.

In the arrangement of Figures 1 and 2 the stop includes a bell crank lever 36 of stamped steel mounted on a pivot 38 carried by the backing plate 12 and which is forked at its end to interlock with the flange 34 of the pivot 16 to prevent axial movement of the pivot, the forked portion of the lever embracing the groove in the end of the pivot 80 16. The space between the arms of the fork is slightly greater than the diameter of the grooved portion of the pivot 16 so that there is a clearance at one side of the grooved portion of the pivot. When the brake is released, the spring 30 pulls the grooved portion of the articulating pin 16 against the upper side of the fork in the end of the lever 36, thus determining the idle position of the shoe 18. The position of the lever 36 may 85 be adjusted to vary the clearance of the shoe 18 with respect to the brake drum by means such as an eccentric 40 extending through the backing plate 12 so that it can be operated from outside the backing plate and 90 which engages the end of the bell crank lever opposite the articulating pin 16.

In the arrangement of Figure 3 there is a lever 136 mounted on a pivot 138 and having its position determined by an eccentric 100

140, in the same general manner as described above, but in this case the lever 136 has its slot arranged in the direction of movement of the articulating pivot 16 so that it closely 5 embraces the grooved portion of the pivot 16 and serves as a guide therefor.

While two illustrative embodiments have been described in detail, it is not my intention to limit the scope of the invention to 10 those particular embodiments or otherwise than by the terms of the appended claims.

I claim:

1. A brake comprising pivotally connected friction means, a pivotally mounted bellcrank lever having one arm engaging the pivotal connection, together with an adjustable device engaging and determining the position of the other arm of said lever.

2. A brake comprising friction elements 20 connected by a pivot, a pivotally mounted bellcrank lever with one arm having a sliding engagement with the pivot, together with an adjustable eccentric engaging and determining the position of the other arm 25 of said lever.

3. A brake comprising shoes connected by a floating pivot having a grooved end, in combination with a positioning lever having one end embracing and interlocking with 30 said grooved end, and an adjustable eccentric for pivotally mounting the lever at its other end.

4. A brake comprising shoes connected by a floating pivot having a grooved end, in 35 combination with a positioning lever having one end embracing and interlocking with said grooved end, and an adjustable eccentric engaging the other end.

5. A brake comprising shoes connected by 40 a floating pivot, a lever having one end embracing the pivot with substantial clearance and an adjustable eccentric providing a pivotal support for the other end of the lever.

6. A brake comprising shoes connected by 45 a floating pivot, a bell crank lever having its knee supported on a fixed pivot and one end embracing the floating pivot with substantial clearance and an adjustable eccentric adaptable for engagement with the 50 other end of the lever.

In testimony whereof, I have hereunto signed my name.

ROY S. SANFORD.
